INVENTOR
Ernest J. Sweetland
BY William P. Hammond
ATTORNEY

UNITED STATES PATENT OFFICE.

ERNEST J. SWEETLAND, OF MONTCLAIR, NEW JERSEY.

WEIGHT.

1,369,057.

Specification of Letters Patent. Patented Feb. 22, 1921.

Application filed April 8, 1919. Serial No. 288,640.

To all whom it may concern:

Be it known that I, ERNEST J. SWEETLAND, a citizen of the United States, residing in the town of Montclair, county of Essex, and 5 State of New Jersey, have invented certain new and useful Improvements in Weights, of which the following is a specification.

In my prior Patent No. 1,285,462, which was granted on November 19, 1918, I have 10 disclosed an apparatus for developing photographic negatives which includes a collapsible tube of rubber or similar material within which the film is unrolled and then treated with a suitable developing agent.

15 The present invention relates to a novel form of weight for carrying the film spool through the tubular developing receptacle and rotatably engaging the film spool so that the film will unwind therefrom as the 20 weight falls through the tubular developing receptacle by the action of gravity.

Among the objects of the invention is to provide a weighted film spool carrier of this 25 character which is simple and inexpensive in its construction, which can be readily applied to film spools of different sizes and which can be collapsed into a comparatively small amount of space when not in use.

With these and other objects in view, the 30 invention consists in certain novel combinations and arrangements of the parts as will more fully appear as the description proceeds, the novel features thereof being pointed out in the appended claims.

35 For a full understanding of the invention, reference is to be had to the following description and accompanying drawings, in which:

Figure 1 is a front elevation of a weighted 40 film spool carrier constructed in accordance with the invention, showing the same in operative position.

Fig. 2 is a similar view showing the carrier in a collapsed condition.

45 Fig. 3 is an end view of the device when in the position shown by Fig. 1.

Fig. 4 is an end view of the device when in a collapsed condition.

Fig. 5 is a view similar to Fig. 1, showing 50 a modified construction in which provision is made for carrying two film spools.

Fig. 6 is a plan view of the modified form of the film spool carrier in a collapsed condition.

55 Fig. 7 is an end view of the construction shown by Fig. 5.

Fig. 8 is a similar view showing the position assumed by the parts when collapsed.

Fig. 9 is a transverse sectional view on the line 9—9 of Fig. 6.

Corresponding and like parts are referred to in the following description and indicated in all the views of the drawings by the same reference characters.

Referring to the embodiment of the invention illustrated by Figs. 1 to 4 inclusive, the numeral 1 designates a weight which has a flat form and is substantially rectangular in shape, the length of the weight being less than the width of the developing 70 tube through which the weight is intended to be dropped. Projecting laterally from the ends of the weight at one edge thereof are ears 2 within which a pair of shafts 4 are slidably and rotatably mounted, said 75 shafts being in alinement with each other and arranged parallel to the longitudinal axis of the weight. The inner ends of the shafts are surrounded by spiral springs 5 which are attached to the ends of the shaft 80 at 6, said springs tending both to slide the shafts inwardly, and also to rotate the shafts in the necessary manner to fold the film spool engaging elements, as will be herein-after described. The outer ends of the 85 shafts are provided with the rigid arms 7 which are arranged at right angles thereto and terminate at their swinging ends in fingers 8 which are adapted to enter the bore or opening of an ordinary film spool S. 90

In order to apply a film spool to the device, the swinging arms 7 are pushed outwardly in opposite directions, thereby sliding the shafts 4 outwardly against the action of the springs 5 and separating the 95 fingers 8 so that the film spool F can be inserted in position between the fingers or removed therefrom. When applying a film spool the arms 7 are released after the film spool has been properly positioned, and the 100 springs 5 then slide the shafts 4 inwardly and cause the fingers 8 to enter the longitudinal bore of the film spool at the ends thereof. The spool S is then rotatably engaged by the arms 8, and in order to stop 105 the device through a tubular tank or chamber, such as that described in my before mentioned prior patent, the weight 1 is permitted to hang from the shafts 4. The free end of the film F is grasped by the finger 110 or otherwise engaged at the upper end of the tubular chamber, so that the film will be

unwound from the spool as the weight 1 drops downwardly through the tubular chamber and carries the film spool S with it. After the film spool has been carried 5 through the tubular chamber, the arms 7 can be pulled apart to release the spool, and the torsion in the spiral springs 5 will then swing the arms toward the weight 1 and into position at the ends thereof. Recessed 10 portions 9 are provided in the weight 1 to receive the fingers 8, so that there are no projections at the top and bottom of the weight and the entire device will fit within a comparatively small space.

15 A slight modification is shown by Figs. 5 to 9, inclusive, in which provision is made for carrying a plurality of film spools. The weight 1^a has an elongated flat formation, as in the previous instance, and a pivot rod 20 10 extends longitudinally through the weight at a point adjacent one edge thereof. A pair of perforated spring arms 7^a are pivotally mounted upon the extremities of the rod 10, while an intermediate arm 11 is pivoted 25 upon the middle portion of the said rod. One face of the weight 1^a is provided at the middle portion thereof with a transversely extending recess 12 which provides for pivoting the arm 11 upon the rod 10, and also 30 forms a chamber to receive the said intermediate arm 11 when the latter is folded against the weight. The outer end of the intermediate arm 11 terminates in a T-head 13 having bearings 14 in opposite ends 35 thereof, said bearings receiving ends 15 of the film spool. The outer ends of the arms 7^a as stated are perforated and as the arms are made of springy material, they may be readily sprung over the projecting ends or 40 studs 15 of the film spool. Obviously, to mount the spool, the arm 11 may be swung from its closed position to the position shown in Fig. 5, whereupon the stud ends 14 of the spools are inserted in the apertures in the T-head, after which the spring 45 arms 7^a are swung outwardly and sprung over the outer projecting studs 15 of the spool. The weighted carrier carrying the film spools is then ready to be dropped 50 through a tubular receptacle or chamber, exactly as previously described. When the device is not in use, the shafts 15 are withdrawn from position and the arms 7^a and 11 swung toward the weight. The arms 7^a 55 fit closely against the ends of the weight, while the intermediate arm 11 is received within the recess 12, a cut away portion 16 being provided at the end of the recess 12 to receive the T-head 13 of the intermediate 60 arm. The device is thus enabled to fold compactly with smooth upper and lower surfaces so that there are no projecting portions to catch upon exterior objects and cause trouble.

65 It will be observed that the form of device

illustrated in Figs. 1 and 2 is capable of accommodating the film spools of varying length, since the spring resisted arms 7 are arranged to separate from each other to any desired extent within the ranges of their 70 movement as permitted by the length of the shafts 4 and the strength or tension of the resisting springs 5.

While I have illustrated and described certain embodiments of the principles of my 75 invention, I do so in an alternative rather than definitive sense as I desire to cover by the appended claims said principles in what-ever manner they may be usefully employed.

Having thus described the invention, what 80 I claim as new herein and desire to secure by Letters Patent, is:

1. A device of the character described, including a weight, and adjustable film spool engaging means carried thereby to permit 85 said weight to be attached to film spools of different lengths.

2. A device of the character described, including a weight, and collapsible film spool engaging means carried by the weight 90 whereby said engaging means may be moved into and out of operative position.

3. A device of the character described, including a weight, and film spool engaging means carried by the weight and foldable 95 against or away from the same.

4. A device of the character described, including a weight, corresponding arms pivotally mounted upon the weight and arranged to fold against or away from the same, and 100 spool engaging means at the swinging ends of the arms.

5. A device of the character described, including a weight, corresponding arms pivotally mounted upon the weight adjacent the 105 upper portion thereof and adapted to be folded against the weight or swung outwardly with respect thereto, and means at the swinging ends of the arms for engaging a film spool.

6. A device of the character described, including a flat weight, corresponding arms pivotally connected to an edge portion of the weight so as to be folded against the weight or swung outwardly into the plane of the weight, and means at the swinging ends of the arms for engaging a film spool.

7. A device of the character described, including a weight, film spool engaging means carried by said weight, spring means coöperatively associated with said film spool engaging means whereby said weight may be attached to film spools having different 120 lengths.

8. In a device of the character described, including a weight, film spool engaging arms slidably engaging said weight, and springs surrounding the sliding ends of said arms tending to resist their movement in a direction away from each other.

9. A device of the character described, including a weight, adjustable film spool engaging means co-operatively associated therewith, said means including a pair of arms slidably and rotatably received within apertures provided in the weight, said arms being provided with inturned ends and spring means resisting the outward movement of said arms in a direction away from each other. 10
10. A device of the character described, including a weight, corresponding arms pivotally connected to the weight and adapted to be folded against the same or swung outwardly therefrom, and spool engaging means at the outer ends of the arms, said weight being recessed to receive the said spool engaging means when the arms are in a folded position. 15
11. A device of the character described, including a weight, corresponding arms pivotally mounted upon the weight and adapted to be folded against the weight or swung outwardly therefrom, spool engaging means carried by the free ends of the arms, and yielding means normally tending to swing the arms against the weight. 20
12. A device of the character described, including a weight, a pair of corresponding arms pivotally connected to the weight and adapted to be folded against the weight or 25
- swung outwardly therefrom, said arms being also movable bodily toward and away from each other, spool engaging fingers at the swinging ends of the arms, and yielding means acting upon the arms to move the same toward each other and hold the fingers in operative position. 30
13. A device of the character described, including a weight, a pair of corresponding arms pivotally mounted upon the weight and adapted to be folded against the weight or swung outwardly therefrom, said arms being movable bodily toward and away from each other, spool engaging 35
- fingers at the outer ends of the arms, and yielding means acting upon the arms to move them toward each other and at the same time swing them toward the weight. 40
14. A device of the character described, including a weight, a pair of shafts slidably and rotatably mounted upon the weight, corresponding arms carried by the shafts and adapted to be swung toward the weight or outwardly therefrom, springs acting upon the shafts to slide the same inwardly and at the same time rotate the arms toward the weight, and spool engaging fingers at the swinging ends of the arms. 50
- 55

ERNEST J. SWEETLAND.
